ROCKET FUEL

Walter Reipold, Geneva, Switzerland, assignor to Ets. Valerca and Kontinitro, Vaduz, Liechtenstein, a corporation
No Drawing. Filed Nov. 2, 1959, Ser. No. 850,067
5 Claims. (Cl. 60—35.4)

This invention relates to improved rocket fuels. More particularly, this invention relates to rocket fuels comprising nitric acid and an organic compound which is efficient in oxygen, e.g. chloronitrobenzene, pyridine, or the like.

A satisfactory rocket fuel must contain both a combustible substance and an oxygen supplier for the combustion of that substance. Generally such rocket fuels require great care in handling because of their tendency to spontaneously ignite at room temperatures. Typical of the prior art rocket fuels are solutions of nitric acid and aromatic polynitro compounds, for example, a solution of nitric acid and meta-dinitrobenzene. The polynitro compound, in this case the meta-dinitrobenzene, is the actual fuel, the nitric acid serving to supply oxygen continuously thereto so as to ensure complete combustion of the dinitrobenzene.

As is well known, the nitration of aromatic compounds is an exothermic reaction resulting in the liberation of a considerable amount of heat. Accordingly, when using a nitric acid solution of m-dinitrobenzene as a rocket fuel the exothermic heat of nitration is not available as energy content in the rocket fuel, so that the heat of combustion of the fuel is considerably less than it would have been had such exothermic energy of nitration been available. This results in a less efficient and less powerful rocket fuel.

Accordingly, it is an object of this invention to provide improved rocket fuels capable of burning with higher heats of combustion than previously thought possible.

Another object is to provide rocket fuels that are stable at ordinary temperatures and not prone to self ignition, whereby they may be readily handled with comparative safety yet without requiring undue precautions.

Additional objects will become apparent hereinafter. In accordance with one aspect of this invention, rocket fuels of unusually high energy content are provided by mixing nitric acid with an organic compound that is both deficient in oxygen and also resistant to nitric acid. Such a compound should be resistant to nitric acid even when the acid is heated to its boiling point. These organic compounds are preferably aromatic or heterocyclic.

Suitable oxygen-deficient aromatic compounds that resist reaction with nitric acid include the halonitrobenzenes, e.g. chloronitrobenzene, and pyridine. If chloronitrobenzene is used, any of the ortho-, meta-, or para-isomers is satisfactory, either alone or as mixed with one or both of the other two isomers.

The mixture of the nitric acid with a suitable oxygen-deficient aromatic compound should preferably contain about 60-80% by weight of concentrated nitric acid and correspondingly about 20-40% by weight of the oxygen-deficient compound.

In accordance with a preferred aspect of my invention, one or more metals or metal hydrides are added to the nitric acid-oxygen-deficient compound solution. Suitable metals include aluminum, boron, and lithium. The corresponding hydrides of these metals are equally applicable. The addition of such metals to the nitric acid-oxygen-deficient compound mixture serves a dual purpose in that (1) the combustion temperature of the fuel is further increased, thereby resulting in greater power and efficiency and (2) the specific weight of the fuel is increased. The amount of metal or metal hydride added is preferably

2

from 1 to 40 percent (by weight) of the weight of the nitric acid-oxygen-deficient compound solution.

The nitric acid-halonitrobenzene rocket fuels of this invention are readily prepared by simply reacting nitric acid with a suitable monohalogenated benzene. The resulting halonitrobenzene compound is resistant to further nitration from excess nitric acid, even when such acid is at its boiling point. Typical of the monohalobenzenes to be reacted with nitric acid is monochlorobenzene. Upon nitration of chlorobenzene with nitric acid there results mononitrochlorobenzene. This is resistant to further attack by the nitric acid.

It will be noted that by a single nitration of chlorobenzene with excess nitric acid there is at once obtained a mixture which is an improved rocket fuel—a fuel of high energy content and proper oxygen balance which, upon ignition, burns with an unusually high heat of combustion. That is, this mixture comprises chloronitrobenzene (the combustible of the rocket fuel) and excess nitric acid. Upon ignition of the chloronitrobenzene combustible the nitric acid functions both as an oxygen supplier and also as a nitrating agent therefor, thereby introducing additional nitro groups into the combustible with the consequent liberation of considerable heat (since this nitration reaction is highly exothermic). Accordingly, the combustion temperature is greatly elevated.

The following examples will more fully illustrate this invention. All parts are by weight unless otherwise indicated.

Example 1

Twenty-five parts of chlorobenzene were added with cooling and agitation to 75 parts of concentrated (98%) nitric acid. The heat of the reaction indicated a mononitration of the chlorobenzene had occurred. There resulted a mixture of three (ortho, meta, and para) chloronitrobenzene isomers along with excess nitric acid. No dinitration occurred. The chloronitrobenzene isomers were each resistant to further nitration, by the nitric acid so that the heat capable of being liberated by any further exothermic nitration was maintained as potential energy of the rocket fuel. Upon proper ignition of this mixture in a rocket the heat of combustion, as determined by the thrust developed, was considerably greater than that developed by a similar fuel wherein m-dinitrobenzene was substituted for the chloronitrobenzene.

Example 2

To 80 parts of concentrated (98%) nitric acid were added, with cooling, 20 parts of pyridine. The amount of heat liberated was precisely the calculated theoretical amount that would be expected to be developed upon the neutralization of a base (pyridine) by an acid. No nitration of the pyridine occurred. The heat capable of being liberated by any subsequent exothermic nitration of the pyridine was maintained as potential energy of the rocket fuel. Upon proper ignition of the above mixture there was developed a very large heat of combustion—much greater than that developed by a similar fuel wherein m-dinitrobenzene was substituted for pyridine.

It will be noted that when a monohalobenzene is treated with nitric acid (Example 1) there is a mononitration resulting in a halonitrobenzene. This halonitrobenzene resists further attack by the nitric acid. However, when pyridine is treated with nitric acid (Example 2) not even mononitration occurs, for the pyridine merely dissolves in the acid. Of course, subsequent ignition of the product of Example 2 does cause exothermic nitration of the pyridine.

3
Example 3

To the mixture of nitric acid and chloronitrobenzene produced in Example 1 were added with stirring 25 parts of powdered aluminum metal. There resulted a mixture that was eminently suitable as a rocket fuel in that it had a high combustion temperature, a high specific weight, and was capable of liberating a considerable heat of combustion.

Example 4

To the solution of pyridine in nitric acid produced by Example 2 were added with stirring 35 parts of powdered lithium hydride. The resulting mixture was also an excellent rocket fuel by virtue of its high specific weight, high combustion temperature, and high heat of combustion.

It will of course be understood that the foregoing detailed description and examples are given merely by way of illustration, and that many variations can be made therein without departing from the spirit of the invention. For example, another halogenated benzene, e.g. bromobenzene, might be substituted for the chlorobenzene of Example 1, leading to a mixture of nitric acid and bromonitrobenzene, which mixture would also exemplify an improved rocket fuel of this invention. Similarly another metal or metal hydride, e.g. powdered boron or boron hydride, could be substituted for the aluminum of Example 3 or the lithium hydride of Example 4.

Having thus described my invention, what I desire to claim and secure by Letters Patent is:

1. A method of producing thrust which comprises ejecting from a reaction chamber the gaseous products produced by the combustion of a fuel comprising a mixture of concentrated nitric acid and a halomononitrobenzene.

2. The method of claim 1 wherein said mixture contains from 60 to 80 weight percent of nitric acid and

4

from 20 to 40 weight percent of said halomononitrobenzene.

3. The method of claim 1 wherein said fuel contains from 1 to 40 weight percent, based on the amount of said mixture, of a material selected from the group consisting of aluminum, boron, lithium, and their hydrides.

4. A rocket fuel consisting essentially of (1) a mixture of from 60 to 80 weight percent concentrated nitric acid and from 20 to 40 weight percent pyridine and (2) from 1 to 40 weight percent, based on the total amount of said mixture, of a material selected from the group consisting of aluminum, boron, lithium, and their hydrides.

5. A rocket fuel comprising a mixture containing from about 60 to 80 parts by weight of concentrated nitric acid and correspondingly from about 20 to 40 parts by weight of halomononitrobenzene, and containing from 1 to 40 parts by weight of a material selected from the group consisting of aluminum, boron, lithium, and their hydrides.
